FIG. I.

FIG. 3.

INVENTOR
CHARLES H. TAYLOR

BY *R. L. Sizemore*

ATTORNEY

UNITED STATES PATENT OFFICE

2,440,160

COUPLING MEANS

Charles H. Taylor, Springfield, Mass., assignor to
 Westinghouse Electric Corporation, East Pittsburgh, Pa., a corporation of Pennsylvania

Application June 16, 1945, Serial No. 599,939

6 Claims. (Cl. 285—173)

1

My invention relates to coupling means for detachably connecting a hose or conduit to the intake or exhaust opening of an air translating apparatus.

One object of the invention is to produce improved coupling means of the type set forth.

A further object of the invention is to devise improved coupling means which can be operated without any skill and with very little effort.

A still further object of the invention is to devise improved, compact coupling means which can be incorporated in the structure of an air translating apparatus without increasing the size of the apparatus and without unduly increasing the cost or the weight thereof.

A still further object of the invention is to produce improved coupling means whereby a hose or conduit may be automatically latched in position by mere insertion of one end of the hose or conduit into the intake or exhaust opening of an air translating apparatus and whereby the hose or conduit may be readily unlatched to permit removal thereof.

These and other objects are effected by my invention as will be apparent from the following description and claims taken in connection with the accompanying drawings, forming a part of this application, in which:

Fig. 1 is a reduced elevational view illustrating the application of the improved coupling means to a tank type suction cleaner;

Fig. 2 is an enlarged fragmentary vertical sectional view showing details of construction;

Fig. 3 is a section on line III—III of Fig. 2; and

Fig. 4 is an enlarged view similar to Fig. 3, certain parts being omitted.

In Fig. 1 of the drawings, there is shown a tank type suction cleaner 10 provided with a lifting handle 12 and mounted on runners 14. The cleaner includes an elongated, open-ended casing 16, the open ends of which are closed by end bells 18 and 20. The casing 16 encloses a suction device and a filter bag, both of which may be conventional and, hence, are not shown nor described. As shown in Fig. 1, the end bell 18 is on the intake side, and the end bell 20 is on the exhaust side of the suction device. The end bell 18 is provided with an opening 22 adapted to receive a fitting or the like 24 which forms part of, or is connected to, one end of a rigid conduit or flexible hose 26 to be connected to the low pressure side of the suction device. The other end of the hose 26 carries any desired suction cleaning tool 28. The end bell 20 is provided with the usual

2

exhaust opening through which filtered air is discharged as shown by the arrow in Fig. 1.

In the embodiment illustrated, the end bell 18 is formed of an outer decorative shell 30, which is finished to harmonize with the finish of the cleaner casing, and an inner shell 32 secured to the outer shell 30 at 34.

The inner shell 32 is provided with an opening 36 which registers with the opening 22. The wall structure defining the opening 36 also forms a seat for retaining a compressible gasket 38 against which the inner end of the fitting 24 is adapted to abut, to effect an airtight connection between the fitting and the interior of the end bell as shown in Fig. 2.

The inner shell 32 carries a mounting plate 40 having flat portions 42 which are secured to the inner shell by rivets or the like 44. The mounting plate has other portions thereof bent at substantially a right angle to the flat portions 42 to form side walls 46 and 48 which are cut out to provide aligning slots 50 adapted to receive pins 52 which project from opposite sides of the fitting 24. To facilitate insertion of the pins into the slots, the mouths or outer ends of the slots are flared as at 54.

In order detachably to lock the fitting in position, I use a latch lever which includes a central yoke or connecting portion 56 and two spaced, parallel side arms 58. The yoke 56 is bent to form a finger piece or push button 60 which is adapted to extend through an opening 62 adjacent the opening 22. The arms 58 are bent to provide generally recessed round portions 64 which overlie the inner portions of the side walls 46 and 48 of the mounting plate 40. The side arms 58 are pivoted to the adjacent side walls 46 and 48 of the mounting plate, as at 66, and are provided with extensions 68 adapted to abut the adjacent edges of the side walls of the mounting plate to limit rotation of the latch lever in counterclockwise direction. The side arms 58 of the latch lever are provided with latch members 70 which, in the position of the lever shown in Fig. 2, are adapted to overlie the slots 50 as shown in Fig. 2. The latch members 70 are provided with longitudinally-slanting edges 72 against which the pins 52 slide as the fitting 24 is inserted through the opening 22, and inclined, transversely-disposed locking edges 74 which are adapted to engage the pins 52 and prevent their withdrawal from the slots 50. It will be understood that the movement of the pins 52 into the slots 50, rotates the latch lever in clockwise direc-

tion, as viewed in Fig. 2, and moves the latch members 10 out of registration with slots 50.

The latch lever is biased to the position shown in Fig. 2 by any suitable spring. In the embodiment illustrated, I use a single spring which is carried by the mounting plate and which acts upon the yoke 56 of the latch lever. As shown, the spring includes a central portion 76 which abuts the underside of the yoke portion 56, and slightly diverging arms 78 and 80 which extend alongside the lever side arms 58 and which are connected, at their converging ends, by loops 82. The ends of the spring arms 80 are bent, as at 84, to engage the vertical edges of the side walls 46 and 48 of the mounting plate, as best shown in Fig. 3. The effect of the spring is to rotate the latch lever about the pivots 66 in counterclockwise direction, so as to move the latch lever to, and retain it in, the engaging position shown in Fig. 2.

Operation

When it is desired to couple the hose to the intake end of the tank type cleaner illustrated, the end of the conduit or the fitting 24 which is connected to the conduit or hose 26, is presented to the opening 22 with the pins 52 on the opposite sides thereof in registration with the flared mouths of the slot 50. As the fitting is inserted through the opening 22 and moved toward the gasket 38, the pins 52 engage the slanting edges 72 of the latch members 10 and push them, against the action of the spring, out of registration with the slots 50. This results in rotation of the latch lever, in clockwise direction, about the pivots 66. When the pins have cleared the slanting edges 72 of the latch members 10, the spring rotates the latch lever in counterclockwise direction to the position shown in Fig. 2. In this position, the transverse edges 74 of the latch members 10 engage the pins 52 and prevent their withdrawal from the slots 50, thus locking the fitting in position. It will be noted that the pins 52 are so spaced from the inner end of the fitting 24 that, when the pins have cleared the slanted edges 72 of the latch members 10, the inner end of the fitting abuts against the gasket 38, and that rotation of the latch lever by the spring, in counterclockwise direction, causes the slanted transverse edges 74 of the latch members to engage the pins 52 and urge the inner end of the fitting 24 into tight engagement with gasket 38. When it is desired to disconnect the conduit or hose from the end bell 18, the push button 60 is moved to the left, as viewed in Fig. 2, thus rotating the latch lever in clockwise direction until the latch members 10 of the lever side arms 58 clear, or are out of alignment with, the slots 50. The fitting can now be withdrawn from the opening 22.

It will be seen from the foregoing that the mechanism described may be used for coupling any two members together and that its application is not limited to the connection of a conduit or hose to the intake or exhaust side of a suction cleaner, or other air translating apparatus. It will also be noted that by means of my improved coupling means, the hose is effectively coupled to the cleaner without the use of bayonet slots or other extraneous fastening devices; and that the hose may be coupled or uncoupled by a straight line movement thereof relative to the cleaner.

It is further pointed out that the hose is automatically coupled by mere insertion thereof through the opening and that it is merely neces-

sary to push the finger piece 69 inwardly to permit withdrawal of the hose from the cleaner opening.

A further advantage is that the spring exerts uniform pressure against the pins on opposite sides of the fitting, thus guarding against wobbling or loosening of the fitting.

While I have shown my invention in but one form, it will be obvious to those skilled in the art that it is not so limited, but is susceptible of various changes and modifications without departing from the spirit thereof.

What I claim is:

1. The combination with a first member having a first opening and a second member insertable into said opening, of means for detachably coupling said members, said means including a pin carried by said second member, a bracket carried by said first member adjacent said opening and having a slot therein adapted to receive said pin, a latch pivoted to said bracket and movable to a first position in which it permits insertion and withdrawal of said pin into and from said slot, and to a second position in which it prevents withdrawal of said pin from said slot, a spring biasing said latch to said second position, there being a second opening formed in said first member, and means carried by said latch and projecting through said second opening for moving said latch to said first position against the action of said spring.

2. The combination with a first member having an opening and a second member insertable into said opening, of means for detachably locking said members together, said means including a pin projecting from a side of said second member, a bracket carried by said first member adjacent said opening and having a slot therein, a latch pivoted to said bracket adjacent the mouth of said slot and movable to a first position in which it overlies said slot between said pivot and the bottom of said slot and into a second position in which it is out of alignment with said slot, means biasing said latch to said first position, said latch being movable from said first to said second position by said pin upon insertion of said second member into said opening, to permit movement of said pin in said slot, said latch being so constructed and arranged that when said second member is inserted into said opening and said pin is inserted into said slot past said latch, said latch is biased to said first position and prevents withdrawal of said second member from said opening, and means for moving said latch to said second position to permit withdrawal of said pin from said slot and disengagement of said members.

3. The combination with a first member having an opening and a second member insertable into said opening, of means for detachably coupling said members together, said means including a pin projecting from a side of said second member, a bracket carried by said first member adjacent said opening and having a slot therein adapted to receive said pin, a lever having one end thereof pivoted to said bracket, a latch carried by said end of said lever and having a first edge portion adapted to lie across the path of movement of said pin into said slot, said latch also having a second edge portion adapted to lie across the path of movement of said pin outwardly of said slot to prevent withdrawal of said pin, said lever being movable to a first position in which said edge portions are

out of alignment with said slot to permit free insertion and withdrawal of said pin into and from said slot, and to a second position in which said edge portions lie across said slot, a spring for biasing said lever to said second position, said lever being movable to said first position by engagement of said pin with said first edge portion during insertion of said pin into said slot, and a projection formed at the other end of said lever for moving said lever to said first position against the action of said spring, said first member being provided with a second opening and said projection extending outwardly through said second opening.

4. The combination with a first member having an opening and a second member insertable into said opening, of means for detachably coupling said members together, said means including a bracket secured at its inner end to said first member and extending in the direction of the opening, with the outer end of said bracket disposed adjacent said opening, there being a slot in said bracket extending from the outer toward the inner end thereof, a pin carried by said second member and adapted to be inserted in said slot, a lever having one end thereof pivoted to the outer end of said bracket, a latch carried by said end of said lever and having a first edge portion adapted to lie across the path of movement of said pin into said slot, said latch also having a second edge portion adapted to lie across the path of movement of said pin outwardly of said slot to prevent withdrawal of said pin, said lever being movable to a first position in which said edge portions are out of alignment with said slot to permit free insertion and withdrawal of said pin into and from said slot, and into a second position in which said edge portions lie across said slot, a spring biasing said lever to said second position, said lever being movable to said first position by engagement of said pin with said first edge portion during insertion of said pin into said slot, there being a second opening in said first member on the side of said slot opposite the side supporting said pivot of said lever, and a projection formed at the outer end of said lever and extending through said opening for moving said lever to said first position against the action of said spring.

5. Coupling means including a first member, a pin carried thereby, a second member, a bracket carried thereby and having a slot therein adapted to receive said pin, a latch having an edge portion overlying the slot, said latch being movable to a first position in which it permits insertion and withdrawal of said pin into and from the bottom of said slot and to a second position in which said latch prevents withdrawal of said pin from the bottom of said slot to lock

said members together, means for normally biasing said latch to said second position, said edge portion of said latch being disposed inwardly of the mouth of said slot and slanted in such a manner as to allow said pin to enter said slot and subsequently cause said latch to be moved to said first position by engagement of said pin with said edge portion, and means for moving said latch to said first position for withdrawal of said pin.

6. The combination with a first member having an opening and a second member insertable into said opening, of means for detachably coupling said members together, said means including

- 15 a pin projecting from a side of said second member, a bracket carried by said first member adjacent said opening and having a slot therein adapted to receive said pin, a lever having one end thereof pivoted to said bracket adjacent the mouth of said slot, a latch carried by said end of said lever and having a first edge portion disposed between the pivot and the bottom of said slot and adapted to lie across the path of movement of said pin in said slot, said latch also having a second edge portion adapted to lie across the path of movement of said pin outwardly of said slot to prevent withdrawal of said pin from the bottom of said slot, said lever being movable to a first position in which said edge portions are out of alignment with said slot to permit free insertion and withdrawal of said pin into and from the bottom of said slot and to a second position in which said edge portions lie across said slot, and a spring for biasing said lever to said second position, the other end of said lever being adapted to be engaged for moving the lever to said first position against the action of said spring, said first edge portion being slanted in a manner to cause said lever to be moved to said first position by engagement of said pin with said first edge portion during movement of said pin toward the bottom of said slot, and said second edge portion being slanted in a manner to cause said pin to move further inwardly into said slot by movement of said lever to said second position.
